UNITED STATES PATENT OFFICE.

HENRY BLASKOPF, OF NEW YORK, N. Y.

GUIDE FOR SEWING-MACHINE HEMMERS.

SPECIFICATION forming part of Letters Patent No. 755,348, dated March 22, 1904.

Application filed March 31, 1903. Serial No. 150,400. (No model.)

To all whom it may concern:

Be it known that I, HENRY BLASKOPF, a citizen of the United States, and a resident of the city of New York, borough of Brooklyn, in the county of Kings and State of New York, have invented a new and Improved Guide for Sewing-Machine Hemmers, of which the following is a full, clear, and exact description.

This invention relates to an improved means for guiding and simultaneously curling a piece of fabric as it is drawn into a hemmer or feller so that after the fabric is once inserted into the machine the services of an attendant are not required, the device being to this extent automatic.

This specification is an exact description of one example of my invention, while the claims define the actual scope thereof.

Reference is to be had to the accompanying drawings, forming a part of this specification, in which similar characters of reference indicate corresponding parts in all the views.

Figure 1 is a perspective view showing the invention in use. Fig. 2 is a plan view illustrating the connection of the device to a hemmer or feller. Fig. 3 is a longitudinal section on the line 3 3 of Fig. 2. Fig. 4 is an enlarged section on the line 4 4 of Fig. 2, and Fig. 5 is a fragmentary perspective view of the guide-plate.

In Fig. 1 *a* indicates the table or work-support of a sewing-machine, which may be of any desired form. *b* indicates the presser-bar, and *c* the needle-bar. In Figs. 1 and 2 *d* indicates a hemmer or feller of any approved construction. Ordinarily it is necessary for an attendant to stand at the machine and roll one edge of the fabric and guide it into the hemmer. My invention does this work automatically, and it is of special value in factories where a large number of machines are in operation, and then an attendant may pass from one machine to another, applying the pieces of work as others are finished. This will dispense with a great number of attendants, as will be apparent.

According to the embodiment here illustrated the invention comprises a base *e*, preferably in the form of a plate and mounted 50 when in use as illustrated in Fig. 1. On the

base *e* is arranged the guide-plate *f*, which has a slot *f'*, receiving a thumb-screw *e'*, working in the base *e*, whereby the plate *f* may be adjusted with respect to the base. Said base is formed with two longitudinally-aligned 55 guides *f'' f''*, these being in the form of lips struck up from the plate itself and turned over the plate, so as to guide the edge of the fabric between the top of the plate and the under sides of the guides. On the guide-plate *f* is 60 arranged the curler-body *g*, which is in the form of a plate having a slot *g'*, through which passes a thumb-screw *f''*, working on the guide-plate *f* and permitting the curler-body 65 to be adjusted longitudinally at will transversely with respect to the guides *f''*. The curler-plate has the curler hingedly mounted thereon, and this comprises a shank *h*, a curved curler proper, *h'*, and a weight *h''* at the end thereof, such parts normally lying as shown 70 in Fig. 4 and the weight serving to keep the curler in active position, while the hinge connection between the shank *h* and the body *g* allows the curler to be thrown over into the inactive position indicated by the dotted lines 75 in Fig. 3.

In the use of the invention the strip of fabric is placed on the guide-plate *f*, with its left-hand edge lying under the guides *f''*. The right-hand edge of the fabric is then turned 80 over, as indicated by the full lines *i* in Fig. 4 and the dotted lines *i'* in Fig. 3, this turned edge being placed under the curler *h'*, after which the fabric is led into and through the hemmer in the usual manner. As the sewing-machine presses the fabric through these parts the right-hand edge of the fabric is automatically curled over in position to be under the hemmer, the same as has heretofore been done 85 by the hand of the attendant. 90

Various changes in the form, proportions, and minor details of my invention may be resorted to at will without departing from the spirit and scope thereof. Hence I consider myself entitled to all such variations as may 95 lie within the intent of my claims.

Having thus described my invention, I claim as new and desire to secure by Letters Patent—

1. A curler-guide for sewing-machine hemmers, comprising a plate, a guide thereon, a 100

curler-body, means for adjustably connecting the curler-body and plate, a curler-shank hinged to the curler-body, a curler proper carried by the shank, and a weight attached 5 to the curler proper.

2. A curler-guide for sewing-machine hemmers, comprising a plate, two guides carried thereby in longitudinal alinement with each other and lying over the plate, a curler-body 10 lying on the plate, means for connecting the curler-body and plate to allow the curler-body longitudinal adjustment transversely of the guides, a curler-shank hinged to the curler-

body, and a curler proper carried by the shank and curved upward and thence downward toward the plate, said shank and curler proper lying over the plate between said guides thereof.

In testimony whereof I have signed my name to this specification in the presence of two sub- 15 scribing witnesses.

HENRY BLASKOPF.
